UNITED STATES PATENT OFFICE.

ERNEST FLAGG, OF NEW YORK, N. Y.

HINGE.

Application filed February 4, 1926. Serial No. 86,041.

This invention relates to a new and improved form of hinge.

An object of the invention is to provide a hinge which is simple, durable and strong and made of a minimum number of parts capable of supporting a maximum weight of door with a minimum defacement of the door and a minimum liability of becoming loosened.

10 The invention is illustrated in the drawings, of which—

Figure 1 is a horizontal section through the door and the jamb showing the hinge in plan view;

15 Figure 2 is a vertical sectional view through the hinge on the line 2—2 of Fig. 1.

The form of the invention shown in the drawings is a preferred form, although it is understood that modifications in the construction and arrangement of the parts and 20 in the character of materials used may be adopted without departing from the spirit of the invention as set forth in the appended claims.

25 In its general aspect the invention comprises a pair of plates that are adapted to be disposed in the door and the jamb, at right angles to the vertical surfaces thereof, these plates having on their inner ends integral 30 turned up cylindrical portions adapted to be disposed in a suitable bore formed in the body portion of the door and the jamb and through which cylindrical portions fastening means such as nails and screws may be 35 introduced into the door and the jamb.

The hinge comprises a pair of plates 10 and 11 which on their inner ends are provided with integrally turned up cylindrical portions 12 and 13, the axes of which are 40 parallel to the front surfaces 14 and 15 of the door and the jamb. Suitable fastening means such as screws 16 and 17 may be introduced through the cylindrical portions to hold the plates in position. The main body 45 portions of the plates 10 and 11 are disposed in sawcuts 18 and 19, formed in the surface

of the door and the jamb and are connected to cup-shaped semi-spherical portions 27 and 28, one of which is nested within the other. A cap 29 bears on the portions 27 to form an 50 ornamental cover and a pin 30 extends beyond the cap 29 and through the semi-spherical portions 27 and 28, which have apertures therein, the lower end of the pin having a washer 31 therein and a split ring 32 extending 55 through a slot or bore in the pin.

Therefore, in applying the hinge it is necessary to provide two sawcuts in the corners of the door and the jamb and then to drill a bore in the edge of each of these members as shown. These bores, however, are not ordinarily visible, since they are formed in the edges of the door and the jamb.

This hinge is light and yet exceedingly strong and will operate with a minimum of 65 friction.

It will be noted that the weight of the door is transmitted to the jamb directly through the nested hinge bearing members 27 and 28, and that the pin 30 serves neither 70 as a pivot nor as a strain-transmitting element. Its sole purpose is to retain the ornamental cover in place, and the hinge would function efficiently without the pin or its cover.

75 What I claim is:

1. As a new article of manufacture, a hinge including a pair of plates adapted to be set horizontally into a closure and closure frame, and nested cup-shaped bearing members 80 integral with the respective plates defining relatively large approximately semi-spherical bearing surfaces.

2. A hinge construction which comprises a pair of hinge plates, each plate being provided on its end with a bearing member, said bearing members adapted to be nested with respect to each other, and a cap, said cap and bearing members having aligned apertures, and a fastening pin extending through said 85 apertures to hold the elements together.

ERNEST FLAGG.
